Primary Examiner — George D. Kirschbaum

Assistant Examiner — Patricia K. Beard

(74) *Attorney, Agent, or Firm* — Neal, Gerber & Eisenberg LLP

(57) **CLAIM**

The ornamental design for a lottery ticket as shown and described herein.

DESCRIPTION

This application is related to the following commonly owned co-pending patent application: U.S. application Ser. No. 18/085,848, entitled “Lottery Tickets Having Different Symbol Sets with Associated Different Sequential Payout Amounts”.

FIG. 1 is a front view of a lottery ticket of one embodiment of our new design; and,

FIG. 2 is a front view of a lottery ticket of another embodiment of our new design.

The dashed broken lines in the figures illustrate portions of the lottery ticket that form no part of the claimed design.

1 Claim, 2 Drawing Sheets
